FORMING TRUING APPARATUS

John Olson, Leicester, Mass., assignor to Norton Company, Worcester, Mass., a corporation of Massachusetts

Application April 27, 1940, Serial No. 331,954

3 Claims. (C.I. 125—11)

The invention relates to forming truing apparatus particularly for forming steep depressions in a grinding wheel.

One object of the invention is to provide a forming truing apparatus of the nature indicated which shall form a more perfect surface on the grinding wheel. Another object of the invention is to eliminate gouges in the surface of the wheel. Another object of the invention is to provide an improved latch for a forming truing apparatus. Another object is to improve the forming bar of patent to D. W. Martin No. 2,187,690. Another object of the invention is to improve the forming truing apparatus of Silven and Cole application Serial No. 256,320. Other objects will be in part obvious or in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings illustrating one of many possible embodiments of the mechanical features of this invention,

Figure 1 is a front elevation of a grinding machine incorporating the forming truing apparatus of the invention;

Figure 2 is a view partly in side elevation and partly in vertical axial section of the forming truing apparatus, the section being taken along the line 2—2 of Figure 4.

Figure 3 is a perspective view of the latches certain parts being arbitrarily spaced apart in order more clearly to show the construction.

Figure 4 is a front elevation of the forming truing apparatus.

Figure 5 is an enlarged elevation of the forming bar.

Figure 6 is a plan view of the forming bar.

Figure 7 is a vertical sectional view through the forming bar taken on the line 7—7 of Figure 6.

As conducive to a clearer understanding of the present invention it is noted that the forming truing apparatus of the aforementioned Martin patent is highly effective to shape a grinding wheel. In the patent the apparatus is shown applied to the footstock of a grinding machine. I have herein shown my forming truing apparatus applied to the wheel slide more in accordance with the disclosure in the Silven and Cole application referred to, but the particular forming truing apparatus above to be described might, as in the Martin patent, be applied to the footstock and

might be applied elsewhere in the grinding machine.

While as above stated the forming truing apparatus of the Martin patent in general operates satisfactorily, there was one latent difficulty therewith which was not perceived at once. This lay in the fact that in order to make the latch operate properly, retrograde movement of the truing tool and the follower caused a slight jogging of the forming tool slide as the follower went over the operating shoulder of the latch thus creating an undesired depression in the wheel. In accordance with the present invention I have overcome this defect without losing any of the advantages of the apparatus of the Martin patent.

Considering now the general structure of a grinding machine, truing apparatus and slides to which my invention may be applied, Figure 1 illustrates in somewhat conventional form a cylindrical grinding machine. The forming truing apparatus of the invention may be applied to many different types of grinding machines but has particular utility in connection with cylindrical grinding machines. It may be applied to automatic grinders, but I disclose herein a hand operated grinding machine since the automatic features may be applied without interference with the forming truing apparatus of the invention. As illustrated in Figure 1, the grinding machine may comprise a base 10 supporting for reciprocation or longitudinal adjustment a carriage 11 which supports a table 12 which may be fastened to the carriage 11 in various positions of angular adjustment, as is well known in the art. Adjustably fastened to the table 12 along ways 13 is a 30 headstock 14 and also a tailstock 15. The headstock 14 may support a driving motor 16 adapted to rotate a face plate 17 through gearing contained in a gear casing 18 and a spindle 19 which is journaled in the headstock 14. Projecting from 40 the face plate 17 is a work holding center 20 in line with and opposite a tail center 21 mounted in the tailstock 15. By means of a hand wheel 22 the tail center 21 may be advanced and retracted toward and from the head center 20, 45 through the medium of screw means, not shown but well known. When the work piece W has been centered in the machine, a lever 23 is used to clamp the tailstock 21 firmly in adjusted position.

For longitudinal adjustment of the carriage 11 there may be provided any suitable device, such as a hand wheel 25 having a pinion gear operating a spur gear 27 which is connected to a pinion gear 28 meshing with a rack 29 fastened to the under side of the carriage 11. The forming truing ap-

paratus of the invention is chiefly used where the grinding is done by the so-called "plunge-cut" method, which involves no relative traverse between the grinding wheel and the work piece.

- 5 Such a grinding operation will form the work piece to a complement or conjugate of the shaped grinding wheel. The hand wheel 25 is used to position the work piece W in the exact desired longitudinal position with respect to the grinding element in order to produce the shaped portion on the work piece in the desired position axially.

Still referring to Figure 1, I show a grinding wheel 30 mounted on a spindle, not shown, journaled in a wheel head 32, the grinding wheel being rotated by a motor 33 and suitable belting in a casing 34 connected to a pulley on the right-hand end of the wheel spindle. I have not shown the wheel spindle and wheel head in any more detail because any conventional drive and support for the grinding wheel may be used, such being well known in the art. In order that the wheel 30 may be fed transversely relative to the work piece W, there is provided a cross feed shaft 35 on which is mounted a ratchet 36 operated by a pawl 37 which is actuated by a cylinder piston hydraulic unit 38. Any other cross feeding mechanism may be substituted for that indicated.

I provide a massive wheel guard 40. This wheel guard 40 is attached to the wheel head 32 and has a large opening 41 at the top bridged by a plate 42 having a smaller opening 43. Fastened to the wheel guard 40 on the upper side thereof, as is best shown at the left-hand side of Figure 2, is a truing base 45. As shown, this base has an upwardly rising inclined web portion 46, a curved portion 47, a pair of bosses 48, and an upper plate portion 49. Still referring to Figure 2, longitudinally centrally disposed in the bottom part of the curved portion 47 is a pivot pin 50. Pivotedly mounted on the base portion 45 by means of this pivot pin 50 is a slideway 51 receiving a cylinder 52. The angular adjustment in a vertical plane of the slideway 51 may be effected by screws 53 whose lower ends engage shelves 54 integrally connected to the slideway 51. This adjustment is usually for minutes of arc only and in order to align the axis of the cylinder 52 with the axis of the wheel 30 more accurately than can be done by machining operations on the various castings. However, the same result can be achieved by adjusting the table 12 on the carriage 11 to a like degree so far as results on the work piece are concerned.

55 The slideway 51 includes dovetailed portions 56 supporting a slide 57 which holds the dressing tool. The slide 57 is of generally hollow construction, as shown in Figure 2, and includes a hollow cylindrical portion 58 as well as dovetailed portions 59 fitting the dovetailed portions 56.

As indicated in dotted lines in Figure 4, a piston 60 is located in the cylinder 52 and has attached thereto a piston rod 61 fastened to a plate 62 which extends rearwardly from the slide 57.

65 Referring now to Figure 2, the cylindrical portion 58 removably supports a sleeve 65 having at the upper end and on the front thereof a shelf 66 and having opposite the shelf 66 at the rear thereof a boss 67 to which is fastened a follower member 68 by means of a bolt 69. The sleeve 65 is slideable vertically in the cylindrical portion 58 but lost motion is preferably eliminated by means of a split bottom portion 70 of the cylindrical portion 58 controlled by a pull screw 71 and a push screw 72. See Figure 4 wherein the cover plate 74 of

Figure 2 is removed. The shelf 66 fits between forked portions 75 of a member 76 attached to the upper part of the cylindrical portion 58 which prevents the sleeve 65 from turning in the cylindrical portion 58. The sleeve 65 is urged downwardly to keep the follower 68 in contact with the form bar hereinafter described by means of a spring 80 fastened to a screw 81 in the shelf 66 and a screw 82 in a lug 83 projecting from the cylindrical portion 58. Merely by uncoupling the spring 80 and loosening the screw 71, the entire unit supported from the sleeve 65 and including the follower 68 may be removed from the machine.

Supported in the upper end of the sleeve 65 is a bearing 90. This bearing is removable but may be firmly locked to the sleeve 65 as it fits within a cylindrical bore thereof including split portions 91 which can be drawn together to clamp the bearing 90. A sleeve 92 is journaled in the bearing 90 and has keyed thereto the hub 93 of a spur gear 20 wheel 94. The hub 93 is mounted on an upper screw threaded portion of the sleeve 92 and is locked on the sleeve 92 rigidly in a vertical direction by means of a pair of nuts 95 and 96. The sleeve 92 is internally threaded and fits on 25 the upper threaded portion 97 of a quill 98 which is keyed by means of a key 99 to the sleeve 65.

Rotation of the gear 94 rotates the sleeve 92 which moves the quill 98 vertically in the sleeve 65, as relative rotation is prevented by the key 99. 30 Positive downward movement can be effected because the sleeve 92 has a shoulder under the bearing 90, as shown. Angular movement of the spur gear 94 is for the purpose of adjusting the vertical position of the quill 98 in the sleeve 65; the sleeve 35 65 moves vertically in response to actuation of the follower 68 to generate the desired contour on the work piece. A dressing diamond 100 is embedded in a nib 101 fitting in a hole in the bottom of the quill 98 and retained therein by means of a 40 screw 102.

For a delicate angular adjustment of the diamond by rotation of the spur gear 94, we provide a knob 103 on the bottom of a shaft 104 located in a vertical bearing 105 which is integral with a 45 plate 106 fastened to the shelf 66. On the upper end of the shaft 104 is a pinion gear 107 meshing with the spur gear 94. A spring-pressed detent, not shown, located in a boss 108, enables the operator to feel the adjustment to a given tooth of 50 the pinion gear 107 or spur gear 94.

In order to effect a dressing of the grinding wheel 30 the dressing diamond 100 is moved in the general direction of the axis of the grinding wheel by moving the slide 57 in response to movement of the piston 60 in the cylinder 52. This may be achieved by the cylinder-piston unit actuated by any fluid pressure apparatus, for example such as diagrammatically illustrated in the application above referred to of Silven and Cole. Although 55 the slide 57 moves rectilinearly, the diamond may be given an irregular motion in a vertical plane by a form bar 109, about to be described, acting upon the follower 68.

Referring now to Figures 5 and 6, I have shown 65 a form bar 109 which has a straight front forming surface 110 merging into a gradual convex curve 111 which in turn merges into a reentrant curve 112 followed by a convex portion 113 having a very steep incline 114 adjacent a perfectly 70 straight portion 115. The portion 110 is nearly but not quite parallel to the motion given by the cylinder piston unit, while the portion 115 is parallel thereto. The follower member 68 will ride over all the portions excepting the portion 75.

114 with no difficulty because they are none of them inclined at more than forty-five degrees to the line of movement of the carriage 11. When it comes to the portion 114 the follower member 5 68 will readily move over it to the left (Figures 5 and 6), but since the portion 114 makes an angle with the straight portion 115 of more than forty-five degrees, the follower member 68 will not ride by this surface 114 to the right without de- 10 forming the parts or possibly breaking one or more of them. I provide a latch 120 to by-pass the follower 68 away over the surface 114.

Referring now particularly to Figure 3, the latch 120 is suitably fastened to a rock shaft 121 which, as better shown in Figures 5 and 6, is journaled in the form bar 109. As shown in Figure 7 this latch 120 is located in a recess 122 in the form bar 109 and when in its operating position secants the portion 114. Consequently the latch 20 120 is supposed to be thrown entirely within the recess 122 when the follower 68 moves to the left but to be automatically returned to the secanting position prior to movement of the follower 68 to the right. This is accomplished by an irregular 25 shaped detent 123 which is loose on the shaft 121 and has a detent point 124 which will be engaged by the follower 68 in either direction of movement thereof. The follower 68 is wide enough to extend across the recess 122 and behind the form 30 bar over the detent 123.

I further provide an operating arm 125 which is suitably clamped to the rock shaft 121 and has a surface 126 for engagement by a pin 127 extending laterally from a portion of the detent 35 124. The operating arm 125 has attached to it a spring 128 which is anchored to a pin 129 extending rearwardly from the form bar 109. Thus the operating arm 125 is urged in a clockwise direction normally placing the latch 120 against 40 a stop pin 130 which extends across the recess 122. When the follower 68 strikes the detent point 124 of the detent 123, the detent 123 is rotated counterclockwise and in turn rotates the operating arm 125 by reason of the fact that the 45 pin 127 extending laterally from the detent 123 is in contact with the surface 126 of the operating arm 125. So, therefore, the follower rotates the detent which rotates the operating arm which rotates the latch 120 thus moving it out of 50 the way of the follower and it will be noted that the detent point 124 is spaced slightly ahead of the leading edge of the latch 120. The detent 123 is maintained relatively to the operating arm 125 in the position shown in the drawings, par- 55 ticularly Figure 3, by means of a spring 131 extending from the right-hand end portion of the operating arm 125 to a pin 132 extending laterally from the detent 123.

In the retrograde motion of the follower 68 it 60 finds the latch secanting the form bar surface 114 and rides over it as the latch 120 forms an easier incline than provided by the portion 114. The grinding wheel of course was shaped in the movement of the parts to the left. But the latch 65 120 may be correlated to the surface of the form bar 109 to give a very smooth ride to the diamond bar because the projection that the follower 68 strikes

is not on the latch 120 but is on a separate part, namely the detent 123. Eventually in the right-hand movement of the follower 68 it strikes the detent point 124 but this is wholly harmless since the detent 123 merely rocks slightly clockwise, 5 the pin 127 lifting from the surface 126 and the spring 131 expanding slightly. When the follower has finally released the detent 123 it simply springs back to its original position, as shown in Figure 3 for example. 10

Referring now to Figures 5 and 6 I have shown duplicate parts at the right-hand side of the form bar 109 which may briefly be identified as latch 120a, shaft 121a, recess 122a, detent 123a, 15 detent point 124a, operating arm 125a, spring 128a, pin 129a, stop pin 130a. These parts are shaped similar to the correspondingly numbered parts without the identifying letter "a" and function as already described.

It will thus be seen that there has been provided by this invention an apparatus in which the various objects hereinabove set forth together with many thoroughly practical advantages are successfully achieved. As many possible embodiments may be made of the above invention and 20 as many changes might be made in the embodiment above set forth, it is to be understood that all matter hereinbefore set forth, or shown in the accompanying drawings, is to be interpreted as 25 illustrative and not in a limiting sense. 30

I claim:

1. In forming truing apparatus, a form bar, a slide, a follower carried by the slide, resilient means causing the follower to engage the form bar, a latch to lift the follower away from the form bar in one relative direction of traverse, and a separate detent arranged to be engaged by the follower and connected to move the latch out of the way when the follower moves in the reverse direction of traverse. 40

2. In forming truing apparatus, a form bar, a follower to ride on said form bar, a latch to lift the follower away from the form bar, a shaft upon which said latch is mounted, a detent and an operating arm, the detent being arranged to be contacted by the follower, the detent being connected through the operating arm to the latch and spring means holding the detent resiliently in a definite relative position to the operating arm while allowing it to be moved out of such position 45 in one direction of travel of the follower, whereby in a given direction of movement of the follower it engages the detent, rocks the operating arm which is connected to the latch and thereby removes the latch from the path of the follower, and in the opposite direction of travel of the follower the detent rocks with relation to the operating arm against the spring means. 50 55

3. In forming truing apparatus, a form bar, a slide, a follower carried by the slide, resilient means causing the follower to engage the form, a latch to lift the follower away from the form bar in one relative direction of traverse and separate means engageable by the follower to swing the latch out of the way in reverse direction of 60 65 traverse.

JOHN OLSON.
